UNITED STATES PATENT OFFICE.

LEON BRASSEUR, OF BROOKLYN, NEW YORK.

EGG-NEST OR FILLER.

979,373.

Specification of Letters Patent. Patented Dec. 20, 1910.

Application filed February 17, 1910. Serial No. 544,424.

To all whom it may concern:

Be it known that I, LEON BRASSEUR, a subject of the King of Belgium, residing at Brooklyn, in the county of Kings and State 5 of New York, have invented new and useful Improvements in Egg-Nests or Fillers, of which the following is a specification.

This invention is designed to provide a novel form of filler or nest for boxes or 10 packages to facilitate the handling and carrying of eggs, whereby the liability of breakage is reduced to the smallest amount possible.

The invention contemplates a filler which 15 may be cheaply and readily formed of a single blank without necessitating the assemblage of a number of parts or the formation of joints and which at the same time may fold into a small space to admit of a 20 large number being arranged in compact form so as not to occupy valuable space.

The invention consists of a filler or nest formed from a single blank of cardboard or similar sheet material comprising a longitudinal web and lateral folds projecting from opposite sides thereof arranged to form spaces so that when the filler is placed in a box, container or package, cells or compartments are provided for reception of individual eggs or like articles to be packed 25 so as to be safely and conveniently handled without damage.

The invention further contemplates a nest or filler consisting of a single blank doubled 30 upon itself midway of its longitudinal edges and having portions of each folded portion laterally deflected to provide extensions which form partitions for subdividing the spaces upon opposite sides of the longitudinal 35 web or partition resulting from folding the blank upon itself longitudinally, said lateral extensions consisting specifically of folds of approximately V-form and said folds being oppositely disposed.

The invention consists of the novel features, details of construction and combination of parts, which hereinafter will be more particularly set forth, illustrated in the accompanying drawing, and pointed out in 40 the appended claim.

Referring to the drawing, forming a part of the application, Figure 1 is a perspective view of a box or carrier provided with a 45 filler or nest embodying the invention. Fig. 2 is a perspective view of the filler or nest. Fig. 55 3 is a plan view of the blank showing

the several cuts and crease lines. Fig. 4 is a transverse section of the filler.

Corresponding and like parts are referred to in the following description, and indicated in all the views of the drawing, by the same reference characters.

The box, package, or container 1 may be of any construction and preferably consists of the type formed of a single blank adapted 60 to be folded into the required form and secured by interlocking flaps in the well known manner.

The present invention relates more particularly to the nest or filler whereby the box 70 is subdivided into cells or compartments for reception of the individual eggs or other articles to be placed therein for safe handling and carrying. The filler or nest is formed of a blank substantially as shown 75 in Fig. 3, the same being oblong and consisting of a strip of cardboard or other sheet material suitable for the purpose. The blank has midway of its longitudinal edges a series of cuts 2 and crease lines 3, the latter being in line with the cuts 2. A series of crease lines 4 extend transversely of the blank at a right angle to the edges thereof and are disposed midway the ends of the cuts 2. Other crease lines 5 extend transversely of the blank parallel with the crease lines 4 and at the extremities of the respective cuts 2. The cuts 2 and the several crease lines 3, 4 and 5 may be formed in any manner. The blanks formed in the manner 80 set forth may be placed one upon the other 85 in a pile.

When it is desired to form a blank into a filler, or nest, it is folded longitudinally along the center line, after which the parts opposite the cuts 2 are folded upon the crease lines 4 and 5, forming the lateral folds 6. When the blank is folded upon itself longitudinally a web 7 is formed interrupted at intervals in its length by lateral folds 6, 90 which unitedly are of a length to extend across the container 1, so as to subdivide the same in conjunction with the longitudinal partition 7 into a plurality of cells or compartments for receiving the individual articles.

The lateral folds 6 are substantially of V-form, hence it will be understood that the length of the filler may vary so that it may be adapted to boxes varying in size within 95 certain limits without necessitating cutting or trimming of the filler to adapt the same 100 105 110

to a smaller box. It is also understood that the construction is such as to admit of the cells or compartments adapting themselves to varying sizes of eggs or other articles, 5 so that a small egg and a large egg may occupy cells or compartments best adapted to their dimensions.

From the foregoing description, taken in connection with the accompanying drawing, 10 the advantages of the construction and of the method of operation will be readily apparent to those skilled in the art to which the invention appertains, and while I have described the principle of operation of the 15 invention, together with the device which I now consider to be the embodiment thereof, I desire to have it understood that the device shown is merely illustrative, and that such changes may be made when desired as 20 are within the scope of the claim appended hereto.

Having thus described the invention what is claimed as new, is:—

A nest or filler for boxes or containers formed of a blank of oblong shape having 25 a series of cuts and crease lines midway of its longitudinal edges, the cuts alternating with the crease lines and in the same straight line therewith, said blank having a series of transverse crease lines arranged at the extremities and intermediate of the extremities of the several cuts, the blank being folded longitudinally in line with the longitudinal cuts and crease lines and having the portions opposite the cuts formed into laterally 30 35 extending V-folds.

In testimony whereof I affix my signature in presence of two witnesses.

LEON BRASSEUR.
